UNITED STATES PATENT OFFICE

2,606,433

DARNING NEEDLE

Gottardo Ercole Bombonato, Milan, Italy

Application July 7, 1950, Serial No. 172,491
In Switzerland July 9, 1949

1 Claim. (Cl. 66—117)

1

This invention relates to a darning needle, especially for mending ladders in stockings, which is provided, at its anterior extremity, with a hook.

This needle is characterized by an oscillating member rotatably mounted in a recess provided in the body of the needle and intended to occupy two positions, said oscillating member being provided with a nose, a projection and a main body, said nose being situated, when said oscillating member occupies its first position, on the way of every thread sliding along the needle towards the hook, the projection being then hidden in said recess, while, when said oscillating member occupies, its second position, the projection obturates the mouth of the hook and the nose is hidden in the recess, said main body extending along the body of the needle when said oscillating member occupies its first position, in such a way that a thread bearing upon it urges to hold said oscillating member in its first position.

The annexed drawing shows, by way of example, one embodiment of the invention.

Figure 1 is a longitudinal section of a needle along line I—I in Figure 2, the oscillating member being in its first position.

Figure 2 is a section along line II—II in Figure 1.

Figure 3 is a section similar to that of Figure 1, but the oscillating member being in its second position.

Figures 4, 5, 6 and 7 show the process of a mending work, in several phases.

The body of the needle is designated by 1; it is constituted by a sheet of metal bent in such a way that the right section of this body has the form of a U, the sides of which are designated by 1^a and the transversal part of which is designated by 1^b. A recess 13 is provided between the sides 1^a. The needle is ended, at its anterior extremity, by a hook. An oscillating member 3 is disposed between the sides 1^a of the body 1. Said member is oscillatably mounted on a pin 4 secured to the sides 1^a. It comprises three parts: a nose 3^a, a projection 3^b and a main body 3^c. The nose 3^a has the form of a hook which is situated, when the member 3 occupies its first position, on the way of every thread sliding along the needle, in the direction shown by the arrow 5, for entering into the hook 2. The projection 3^b is then hidden in the recess 13. During this displacement, the thread catches obligatory the nose 3^a and drives the member 3 in rotation for bringing it into its second position, in which the projection 3^b obturates the mouth of the hook 2. When the member 3 occupies its first position, its

2

main body 3^c extends along the body 1 of the needle. The edge 3^d of this main body projects out of the body 1 in such a way that a stitch bearing upon it urges to prevent the member 3 from going from its first position into its second position. A notch 6 is provided in the sides 1^a. This notch has for object to slow the advance of the stitch along the needle. The member 3 is ended by a shoulder 3^e intended to prevent a thread from going up along the needle beyond the body 3^c. A hole 7 provided in the oscillating member 3 is intended to lighten said member. 8 designates a solid bar situated between the sides 1^a and riveted at 9. This bar ensures the rigidity of the posterior part of the needle and constitutes a handle. The hook 2 is made thinner at 10, slightly under the axis of the needle, so that the thread situated in this hook occupies this thin place 10, what makes easier the operation of the needle.

This operation is the following:

The needle is introduced in a stitch 11, ready to be dropped, under the last stitch which has already been dropped, designated by 12. The stitch 11 abuts against the projection 3^b and brings the member 3 into its first position. It is necessary to drive the needle rather deeply so that the stitch 11 reaches at least the notch 6; it may even reach the body 3^c of the member 3; during this movement, the thread 12 came behind the nose or hook 3^a (Figure 5). The needle is then pulled out. The threads 11 and 12 slide simultaneously along the body of the needle, in the direction of the hook 2. The thread 12 enters into the hook 3^a (Figure 6). The member 3 is prevented from oscillating by the stitch 11 which bears on the edge 3^d of the body 3^c. A certain tension of the thread 12 then takes place. As soon as the stitch 11 has passed the bottom of the notch 6, the member 3 is released and occupies rapidly its second position, the hook 3^a entering into the recess for hiding therein. This hook 3^a leaves then the thread 12 which is situated at the mouth of the hook 2 and is thus obliged to enter into it. The tension of the thread 12 prevents it from leaving prematurely the hook 3^a. During the rotation of the member 3, the projection 3^b passes before the stitch 11 and obturates the mouth of the hook 2, so that the stitch 11 leaves the needle (Figure 7). If the thread 12 had accidentally not entered into the hook 2, the member 3 had not begun to rotate and it would be the stitch 11 which should have entered into the hook 3^a and then into the hook 2 (Figure 4). The operation

should have to be done again, but the stitch 11 should not have been dropped.

The stitch 11 thus cannot leave the needle before the thread 12 has entered into the hook 2.

In all the needles known up until today, the most frequent wrong operation, viz. the non-catching of a thread, produces the outlet of the thread out of the needle and consequently the dropping of the just formed stitch and generally of several other stitches.

The needle does not present this drawback and can be operated without entailing an apprenticeship. A wrong carried out operation has simply to be repeated, without the work precedently carried out being disturbed.

What I claim is:

In a darning needle, especially for mending ladders in stockings, ended at its anterior extremity by a hook, a body of this needle, a recess in said body, an oscillating member rotatably mounted in said recess and intended to occupy two positions, said oscillating member being provided with a nose, with a projection and with a main body and said oscillating member being arranged in such a way that when it occupies its first position, said nose is situated on the way of every thread sliding along the needle towards the hook, and the projection is then hidden in said recess,

while, when said oscillating member occupies its second position, the projection obturates the mouth of the hook and the nose is hidden in said recess, said main body extending along the body 5 of the needle when said oscillating member occupies its first position, in such a way that a thread bearing upon it urges to hold said oscillating member in its first position, the main body of said oscillating member ending by a shoulder 10 intended to prevent the thread bearing upon said main body from going up along the needle beyond said main body.
